UNITED STATES PATENT OFFICE.

HARRISON D. BOYER, OF FERNROCK, PENNSYLVANIA, ASSIGNOR, BY MESNE ASSIGNMENTS, TO LEANDER W. RIDDLE, OF GLEN RIDDLE, PENNSYLVANIA.

LUBRICATOR.

1,304,535.

Specification of Letters Patent. Patented May 27, 1919.

Application filed February 16, 1916, Serial No. 78,577. Renewed January 11, 1919. Serial No. 270,757.

To all whom it may concern:

Be it known that I, HARRISON D. BOYER, a citizen of the United States, residing at Fernrock, in the county of Philadelphia and State of Pennsylvania, have invented new and useful Improvements in Lubricators, of which the following is a specification.

My invention relates to new and useful improvements in lubricators, and especially to that class of such lubricators as utilize a plunger for forcing the lubricant into the bearing, and a semaphore adapted to signal when the feeding of the lubricant ceases.

My invention has for its object to provide an improved construction of plunger-actuating mechanism, for lubricator cups, having a new mode of operation relatively to the cup body and to a semaphore or signal device forming an adjunctive element of the plunger actuating means; and to these ends my invention consists in dividing the plunger carrying and actuating element so that it shall consist of a plunger rod and co-acting tubular means, an operating screw-threaded connection between one of said divided elements and the apertured top wall of the cup body and an operating sliding connection between the other of said divided elements and the cup body, one of said divided elements passing entirely through the other, and being adjustable relatively to each other by the threaded member thereof, in combination with a compression spring adapted to be compressed by operation of the screw threaded connection between one of said divided plunger actuating elements and the cup body, and to be released and thereby automatically actuate the plunger, by means of the reversely operating sliding connection between one of said elements and the aperture in the cup body.

In order that those skilled in the art to which this invention appertains may understand how to make and use the same, I will describe its construction in detail, referring by numeral to the accompanying drawing forming a part of this application, in which—

Figure 1, is a side elevation of one form of lubricating cup made in accordance with my improvement.

Fig. 2, is a central vertical section thereof.

Fig. 3, is a detail view of the plunger and a portion of the stem, and barrel, illustrat-

ing the manner of locking the barrel against 55 accidental rotation after it has been adjusted.

Fig. 4, is a central vertical section of a still further modified form of my invention, showing the position of the operating parts 60 when the cup is empty or off feed.

Fig. 5, is a similar view taken at right angles to Fig. 4, and showing the position of the operating parts when the cup is on feed.

Fig. 6, is a section at the line 19—19 of Fig. 5.

Fig. 7, is an elevation of the top of the cup, showing the semaphore omitted.

Since it is obvious that various forms of 70 construction may be designed embodying my improvements, I therefore do not limit myself to the particulars here shown, constructions being shown and described only for the purpose of illustrating my invention. 75

In carrying out my invention as here shown 1 represents the bottom of the cup provided with the usual nipple 2 for securing it upon a bearing by threading the nipple into a corresponding hole in said bearing. Above this nipple is located a regulating plug 3 intersecting the outlet passage 4 and having a hole 5 therethrough for alignment with the passage 4 when it is set for full feed and adapted to be turned crosswise 85 of the passage for reducing or cutting off the feed.

6 is the top of the cup and in the construction here shown intended to receive and supply the grease, but which may obviously be only a shallow cap fitted to an extended body. 7 is the plunger fitted to slide in the top and expel the grease therefrom. 8 represents a tubular member threaded through the top of the cup and through this 95 member passes slidably the stem 9 which projects upward from the plunger and has attached thereto the signaling semaphore 10.

Between the tubular member 8 and the plunger is interposed a spring 11, so that 100 when the grease is forced downward by the plunger through the action of the spring until the limit of the stroke is reached the semaphore will be thrown to a vertical position as shown in the drawings, while thereafter the tension of the spring upon the plunger may be reset by the screwing upward of the tubular member, which latter

operation will again compress the spring, thereby resetting the cup and at the same time lowering the signaling semaphore, all of which may be readily understood.

5 The tubular member 8 may be beveled off as indicated at 14 in Fig. 3, so that the spring 11 may retard its movements, thus preventing it from backing off after being set.

10 In Figs. 4, 5, 6 and 7 I have shown a modification of my invention which, however, is merely a reverse arrangement, but in the same operative relation, of the divided plunger actuating members, to each other 15 and to the cup element; and in which the stem 9 is threaded through the tubular member 8 of Fig. 2 and which, in this arrangement of that element is marked 27, which latter is slidable relatively to the container 20 and is provided with a flange 28 upon which the spring 11 is seated, the upper end of the slidable member having pivoted thereto the semaphore 10, as in the other form shown in Fig. 2.

25 In this form of my device, the top wall of the cap is given a central concavity or depression surrounding the aperture, and the semaphore 10 is in the form of a ring mounted on the free end of the tubular sliding member the ring being brought into contact within the concavity surrounding said aperture.

The operation of this construction is as follows:—

30 When the cup is empty and ready to be filled and set, the slidable member and semaphore will assume the position shown in Fig. 4, but when the cup is filled with a lubricant as shown in Fig. 5, the manual rotation of the plunger-carrying stem 9 will force the slidable tubular member 27 upward against the action of the spring, lowering the semaphore 10, and as the lubricant is forced from the cup by the action of the 35 spring, a plunger and connected stem will carry the tubular member slidably downward within the aperture in the top of the cup and finally throw the semaphore to raised or signal position, when the operation 40 of resetting the cup may be repeated.

45 In Fig. 7 the same construction as just described is shown, in which the semaphore 10 is omitted, and the rise and fall of the slidable member 27 utilized as the signal to indicate when the cup is off or on feed as will be 50 readily understood.

55 While I have shown and described these designs for grease cups as standing in a vertical position, it is obvious that they may be

used in a horizontal or at any desired angle 60 which is often found necessary in practice.

Having thus fully described my invention, what I claim as new and useful, is—

1. A lubricator comprising in combination a container having a top wall centrally apertured, a plunger mounted to reciprocate in said container, and plunger-actuating means consisting of a tubular member inferiorly threaded and slidably supported in said aperture in the container and projecting therethrough, a screw threaded rod passing entirely through said threaded tubular member and adapted to be operatively rotated by its projecting end, its opposite end having fixed connection with the plunger, for moving said plunger in one direction, and a spring adapted to be compressed by the said slidable means and operating under said tensional compression to automatically force said plunger in an opposite direction. 80

2. In a device of the character stated, a container having a top wall centrally apertured, a plunger reciprocally movable in the container, slidable means projecting through said aperture in the container and having operative connection with the plunger, supporting devices for said slidable means, a spring adapted to be put under tension by the manual adjustment of said operatively connected plunger and slidable element and 90 to be automatically released from tension by the feed of the container contents to complete the stroke of the plunger in a discharging direction, and a semaphore movably connected to said slidable means and adapted 95 thereby, on such completion of the discharging stroke, to move said semaphore to a signaling position.

3. A lubricator comprising a container having an apertured central concavity in its top wall, a plunger, a spring to actuate the same in a discharging direction, plunger-carrying means operating to compress said spring, said means consisting of a sliding tubular member and a threaded member, one 100 adjustably movable within the other, and both slidable as one, within said aperture in the container wall, and a semaphore pivoted on the free end of said slidable member and adapted to be brought into signaling contact 110 with said apertured concavity.

In testimony whereof, I have hereunto affixed my signature in the presence of a subscribing witness.

HARRISON D. BOYER.

Witness:

MOLLIE TOBIAS.
